UNITED STATES PATENT OFFICE

CHARLES W. EEBLING, OF NEW YORK, N. Y., ASSIGNOR TO GENERAL TALKING PICTURES CORPORATION, OF NEW YORK, N. Y., A CORPORATION OF DELAWARE

MOTION PICTURE SCREEN

Application filed April 1, 1931. Serial No. 527,018.

The present invention relates to improvements in motion picture screens, one object of the invention being the provision of a portable support therefor, whereby when the screen is not in use the support is readily knocked down and collapsed to be stored for easy shipment, or portability.

Another object of this invention is the provision of a trunk carried portable screen and mount in which the trunk per se forms the main base, and which when the screen is in use, supports the adjustable and collapsible members so that the screen may be disposed in the desired position during the projection of pictures, yet permitting the screen to be readily knocked down and the supporting portions thereof collapsed and placed within the trunk.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings:—

Figure 1 is a side elevation of the complete mount with the screen in position, a portion of one wall of the trunk thereby being broken away to show the pedestal carried bodily.

Figure 2 is a rear elevation of the screen and the support thereof.

Figure 3 is an enlarged view of the arm supporting casting per se and Figure 4 is a view showing the screen collapsed in the trunk.

Referring to the drawings, the numeral 4 designates the trunk provided with a lid 5.

Attached to the bottom wall 6 of the trunk and central of the trunk is a metal casting forming a pedestal 7 having the attaching lugs 8 and the central upwardly projecting apertured boss 9.

In order to provide a removable standard or support, two rods 10 and 11 are telescopically attached as at 12 so that the lower end of the rod 10 may be projected into the boss

9 and thus support the rods 10 and 11 in a vertical position.

A screen supporting casting 13 is provided with a channeled lug 14 to receive the upper end of the rod 11 which may be adjustably attached therethrough through the medium of a thumb screw 15. By this means the casting 13 is supported at the desired height above the trunk.

Formed in the body of the casting 13 adjacent the respective corners thereof and at a slight incline are four bores 16 to receive the inner ends of the respective supporting rods or arms 17, which inner ends are anchored in the proper adjusted relation by means of thumb screws 18.

A motion picture screen 19 preferably rectangular in shape and provided with grummets 20 adjacent the corners thereof is adopted to have the grummets fit over an outwardly bent or hooked terminal 21 of the arms or rods 17 which rods are then adjusted longitudinally to stretch and hold the screen in proper position for projection. This screen when not in use is adapted to be folded centrally and longitudinally into a double thickness and then rolled from one end so as to be readily packed within the trunk 4.

From the foregoing description taken in connection with the drawings, it is evident that with the present device a desirable adjunct to a portable motion picture apparatus is provided and one wherein a trunk or container is made to serve two purposes, that is to transportably support the screen and its mount in knocked down shape or to act as a base for the mount when the same is holding the screen for use.

What is claimed is:

1. The herein described portable motion picture screen including a pedestal having an open ended socket, a tubular standard detachably mounted therein, a rectangular casting provided with a channeled lug centrally of and upon one side thereof for receiving the upper end of such standard, four thumb screws mounted adjacent the corners of said casting, four supporting rods adjustably attached to the casting by said thumb screws, said rods when extended and forming

the four diagonals of the casting, the ends thereof being bent outwardly to form hooks, and a motion picture screen adapted to engage said hooks to be held in extended position by said rods.

2. The herein described portable motion picture screen as claimed in claim 1, in which the pedestal is mounted within a trunk, the dimensions of which are such that the open ended socket is below the upper edges of the side walls thereof, while the lateral length of the pedestal is substantially the width of the trunk, the trunk forming with the pedestal an additional base.

16 In testimony whereof I affix my signature.
CHARLES W. EBELING.
